FLEXIBLE PLASTIC FILM

David Laska, New York, N. Y., assignor to Texileather Corporation, Toledo, Ohio, a corporation of Delaware

Application May 31, 1951, Serial No. 15,352

Term of patent 14 years

(Cl. D87—3)

To all whom it may concern:

Be it known that I, David Laska, a citizen of the United States, residing at New York, in the county of New York, State of New York, have invented a new, original, and ornamental Design for Flexible Plastic Film, of which the following is a specification, reference being had to the accompanying drawing, forming part thereof.

The figure is a face view of a flexible plastic film, showing my new design. The instant film is comprised of two flat surfaces and is of no appreciable thickness.

I claim:

The ornamental design for a flexible plastic film, substantially as shown and described.

DAVID LASKA.
